(57) **CLAIM**

The ornamental design of the dual hay spear, as shown and described.

DESCRIPTION

FIG. 1 is a top perspective view illustrating my new design having dual hay spear elements thereof in a lowered position.

FIG. 2 is a front elevational view of my new design with the dual hay spear elements thereof in the lowered position.

FIG. 3 is a rear elevational view of my new design with the dual hay spear elements thereof in the lowered position.

FIG. 4 is a left side elevational view of my new design with the dual hay spear elements thereof in the lowered position.

FIG. 5 is a right side elevational view of my new design with the dual hay spear elements thereof in the lowered position.

FIG. 6 is a top plan view of my new design with the dual hay spear elements thereof in the lowered position.

FIG. 7 is a bottom view of my new design with the dual hay spear elements thereof in the lowered position.

FIG. 8 is a top perspective view of my new design with the dual hay spear elements thereof in a raised position.

FIG. 9 is a front elevational view of my new design with the dual hay spear elements thereof in the raised position.

FIG. 10 is a rear elevational view of my new design with the dual hay spear elements thereof in the raised position.

FIG. 11 is a left side elevational view of my new design with the dual hay spear elements thereof in the raised position.

FIG. 12 is a right side elevational view of my new design with the dual hay spear elements thereof in the raised position.

FIG. 13 is a top plan view of my new design with the dual hay spear elements thereof in the raised position; and,

FIG. 14 is a bottom view of my new design with the dual hay spear elements thereof in the raised position.
